UNITED STATES PATENT OFFICE.

MAURICE F. GRIFFIN, OF LOS ANGELES, CALIFORNIA.

TRUNK.

Application filed January 28, 1924. Serial No. 688,965.

To all whom it may concern:

Be it known that I, MAURICE F. GRIFFIN, a citizen of the United States, residing at Los Angeles, in the county of Los Angeles and State of California, have invented new and useful Improvements in Trunks, of which the following is a specification.

This invention is applicable to various trunks, but is more particularly designed for automobile trunks; that is to say, trunks adapted to be fitted in closely to the rear end of automobiles having bodies with back inclined; and also adapted to be fitted onto and carried on the back-rack or running board of an automobile.

An object of the invention is to make a trunk that is positively water and dust proof in itself when closed.

Another object is to provide a trunk, the body of which is so covered as to improve its appearance over other trunks and to avoid any joints or piecing at the upright corners of the trunk.

Another object is to provide a trunk in which the joined edges are inconspicuously connected.

An object is to provide a trunk having a single piece body cover.

Other objects, advantages and features of invention may appear from the accompanying drawings, the subjoined detail description and the appended claims.

The accompanying drawings illustrate the invention.

Figure 1 is a perspective rear view of a closed trunk constructed in accordance with this invention.

Fig. 2 is an enlarged fragmental section on line 2—2, Fig. 1, showing the arrangement of the cover and lining at the water and dustproof hinge joint between the lid and the top of the body.

Fig. 3 is a view analogous to Fig. 2 with lid open.

Fig. 4 is a reduced view of a blank for the one-piece cover for the lid and the hinge joint.

Fig. 5 is a view of the one-piece cover for the trunk body.

Fig. 6 is a perspective front view of the trunk, open.

Fig. 7 is a fragmental vertical transverse section of the upper portion of the trunk with lid partly open in solid lines and fully open in broken lines.

Fig. 8 is a broken vertical transverse section of the closed trunk.

Fig. 9 is an enlarged fragmental view showing the water-proof and dust-proof joint between the front edge of the lid and body when the trunk is closed.

The body 1 of the trunk is constructed with a base 2 formed of well known three or more ply veneer, not detailed in the drawings.

Said body comprises a bottom, and, connected to the bottom and to each other is a front wall and end walls arranged perpendicular to each other and to the bottom; and a back wall connected to the bottom and to the end walls, and inclined forwardly so that the trunk is wider at the bottom than at the top; and so that the inclined back of the trunk will fit flush to and under the outwardly inclined back of an automobile.

Said body is provided at the rear top portion with a riser 3 to which the lid 4 is hinged; and the lid is formed so that it will fit down flush on the front and side walls, and is provided with a notch 5 that fits over the rims 5' of the front and side walls when the lid is closed, said lid being constructed with the usual base of veneer 2'.

The lid is hinged at its rear edge to the top of the trunk by a piano hinge 6 extending from end to end of the trunk and arranged to cover the joint between the body cover 7 and the lid cover 8 which are of suitable flexible material glued or otherwise cemented in place.

In order to apply to the base 2 of the trunk body, the body cover 7 with a minimum showing of joints, I have invented a novel body cover blank which is applicable to this form and design of trunks, and which is exemplified in Fig. 5, and which comprises a front panel *a*, a bottom panel *b* integral with and projecting from one bottom edge of the front panel *a*; end panels *c*, *c'* integral with and extending from the ends of the front panel, and sectional back panels or flaps *d*, *d'* integral with the edges of the end panel *c*, *c'* respectively and jointly equal in length to the bottom panel.

The body cover panels *c*, *c'*, *d*, *d'* are provided with bottom body cover laps *e*, *e'*, *f*, *f'*, and the material is adapted to be bent onto the base 2 of the trunk body with the line *g* of the bend between the panels and the flaps formed continuously from end to end of the

blank. Said panels are provided with top flaps $h, i, i', j, j', k, k', m$ and m' which are all practically of the same width; and in the form of trunk shown, the top flap h and the panel a extend from end to end of the front of the body; and the ends of flap h are determined by slits n which separate the top flap h from the adjacent top flaps i, i' , of the end panels c, c' respectively.

10 The panels c, c' are each provided with three flaps i, j, k and i', j', k' respectively. The flaps i and j and likewise the flaps i', j' are separated from each other by slits o, o' and the flaps j, k are separated from each other by the notch p , and the flaps j', k' are separated from each other by the notch p' while the flaps k and k' of the end panels c, c' respectively are separated from the adjacent back top flaps m, m' respectively by notches q, q' .

15 The panels d and d' and the adjacent portions r, r' of the end panels c, c' may be of any height relative to the front panels a determined by the height of the riser 3 of the trunk body; said back panels being made wide enough from the bottom fold line g to the top fold line s to extend to the top of the back of the trunk; and the top back folds m, m' being equal in width to the 20 space between the top rear corner 9 of the trunk body and the hinge receiving edge 10 of said body.

25 The lid cover is cut according to the desired shape of the lid and comprises the top panel t , the top end flaps u, u' at the ends of the top panel t ; the inside end lid laps v, v' and the rear edge lid laps w, w' .

30 The front edge of the top panel t is integral with the front lid panel x having end flaps y, y' and the folding panel z is integral with the lower edge of the front lid panel x . The cover is made of any suitable waterproof material such as enameled duck, kerator, fabrikoid or other waterproof material.

35 The lining 11 may be of any suitable dust excluding material and applied to the trunk body in any well known way.

40 Base 2' of the lid is of the same thickness as the base 2 of the body and said lid is provided at its edges with outside and inside valences 12, 13 which may be of sufficiently gauged hoop steel to afford the required strength; and they are arranged to form a 45 channel 5 adapted to receive the top edge 5' of the body when the lid is closed.

45 The transverse faces of the outside valence 12 are straight so that when the lid is closed it will fit the outside of the trunk body.

50 The inside valence 13 is struck up at 14 so as to form an inwardly flaring rim to receive and wedge upon the top edge 5' of the open portion of the trunk to form a practically air-tight and water-tight and dust-proof joint.

55 The top panel t of the lid cover is provided with a hinge lap t' of sufficient width to extend from the rear edge of the lid base 2' in the form of a loop 15 practically equal in width to the thickness of the bases 2 and 2' and to extend over the hinge receiving edge 10 of the front edge of the trunk top and to the rear edge 17 of hinge 6.

60 In practical operation the cover shown in Fig. 5 is fastened to the base of the trunk body by gluing the bottom panel b in place with the front panel a at the front of said trunk body; the end panels c, c' are then smoothly glued onto the ends of the base and the sectional back panels d, d' are then glued 80 and smoothed onto the back of the trunk body and the outer ends are brought together to form a butt joint 18 extending from bottom to top of the back of the trunk, see Fig. 1.

65 The bottom back flaps e, e', f, f' are then smoothly glued onto the bottom panel b and the top flap h of the front panel is turned over the top edge of the front of the trunk base and is smoothly glued to the top and inside of said front edge and this is likewise done with the flaps m, m', k, k', j, j' and i, i' the slits and notches n, o, p, q allowing this to be done.

70 The lid cover 8 is then glued to the lid base 2' in a manner that will be readily understood by the skilled mechanic and the front edge of the hinge 6 is fixed to the rear edge of the lid outside of the cover which has been glued thereonto. Then the hinge lap t' is bent into the fold 15 and its edge is brought to the rear edge 17 of the hinge 6, and is smoothly glued to the edge of the flaps m, m' . The rear edge of the hinge 6 is then fastened to the riser 3 of the body 1 by suitable fastening means as the rivets 19, and the trunk is complete.

75 I claim:

1. The improvement in trunks set forth comprising a body; a lid hinged to and spaced from said body at its hinged edge; a covering for said body; and a covering for said lid having a fold in the space between said lid and body and being secured to said body.

80 2. The improvement in trunks set forth comprising a body having a rim; a one piece covering to said body, said covering provided with over-laps to fit over and enclose the rim of said body; a lid having a rim; a one piece covering to said lid, said lid covering provided with over-laps to fit over and enclose the rim of said lid; and a hinge connecting said lid to said body.

85 3. The improvement in trunks set forth comprising a body having a rim; a one piece dust and rain proof covering to said body, said covering having over-laps adapted to extend over and enclose the rim of said body; a lid having a rim; valances secured

to said lid at the rim thereof, said valances arranged to form a channel adapted to receive the rim of said body when said lid is closed; a one piece dust and rain proof covering for said lid, said covering extending into the channel of said lid; and a hinge connecting said lid to said body, said hinge arranged outside of the covering of said lid and body:

10 4. A one piece cover for trunks of the character set forth, including a body cover, comprising a front panel, a bottom panel integral with and projecting from one bottom edge of said front panel; end panels integral with and projecting from the ends of the front panel, sectional back panels integral with the edges of the end panels, respectively, and jointly equal in length to the bottom panel and top flaps extending from 20 said front panel, end panels and sectional back panels and adapted to fit over the rim of the body.

5. A body cover for trunks of the character set forth comprising a front panel, a top flap integral with and extending from the upper edge of said front panel, the ends of said top flap being determined by slits; end panels integral with and extending from the ends of the front panel; top flaps *i*, *j* and *i'*, *j'* extending from the upper edges of said end panels and respectively separated from each other and determined by slits; other top flaps *k*, *k'* extending from the upper edge of said end panels, said other flaps being adjacent to and separated from said flaps *j* and *j'* by notches *p*, *p'*; flaps integral with and extending from the lower edge of said front and end panels and adapted to extend around the lower edge of the trunk and be fastened to the underside thereof, and flaps integral with and extending from said end panels and adapted to extend around the back edge of the trunk and be fastened to the back or rear side of said trunk.

extend around the lower edge of the trunk and be fastened to the underside thereof.

6. A body cover for trunks of the character set forth comprising a front panel, a top flap integral with and extending from the upper edge of said front panel, the ends of said top flap being determined by slits; end panels integral with and extending from the ends of the front panel; top flaps *i*, *j* and *i'*, *j'* extending from the upper edges of said end panels and respectively separated from each other and determined by slits; other top flaps *k*, *k'* extending from the upper edge of said end panels, said other flaps being adjacent to and separated from said flaps *j* and *j'* by notches *p*, *p'*; flaps integral with and extending from the lower edge of said front and end panels and adapted to extend around the lower edge of the trunk and be fastened to the underside thereof, and flaps integral with and extending from said end panels and adapted to extend around the back edge of the trunk and be fastened to the back or rear side of said trunk.

7. The improvement in trunks set forth comprising a body; a lid hinged to and spaced from said body at its hinged edge; a hinge lap secured at one edge to said cover and having a fold in the space between said lid and body and having its other edge secured to said body.

In testimony whereof, I have hereunto set my hand at Los Angeles, California, this 10th day of January, 1924.

MAURICE F. GRIFFIN.
